UNITED STATES PATENT OFFICE.

THOMAS E. STURTEVANT, OF DOVER, NEW JERSEY, ASSIGNOR TO MCKIERNAN-TERRY DRILL COMPANY, OF DOVER, NEW JERSEY, A CORPORATION OF NEW JERSEY.

ROCK-DRILL.

1,265,133.

Specification of Letters Patent.

Patented May 7, 1918.

Application filed April 21, 1917. Serial No. 163,550.

To all whom it may concern:

Be it known that I, THOMAS E. STURTEVANT, a citizen of the United States of America, and a resident of Dover, Morris county, and State of New Jersey, have invented certain new and useful Improvements in Rock-Drills, of which the following is a specification, reference being had to the accompanying drawings, forming a part 10 thereof.

My invention relates to improvements in rock drills, and especially to that type of rock drilling engines which are known as hammer drills. Its object is to provide a 15 simple and efficient apparatus of this kind of rugged construction.

Another object is to improve upon the valve mechanism and to simplify and shorten the fluid passages, and to provide a 20 simple arrangement for automatically carrying the valve past its central position.

In order that my invention may be thoroughly understood I will now proceed to describe the same in the following specification and then point out the novel features 25 thereof in appended claims.

Referring to the drawings:

Figure 1 is a sectional side elevation of a hammer drill made according to and embodying the present invention.

Fig. 2 is a front elevation of the same apparatus.

Fig. 3 is a sectional side elevation of the valve mechanism on a larger scale.

Fig. 4 is a sectional front elevation of the same mechanism.

Figs. 5, 6, 7, 8, 9, 10 and 11 are sectional plan views of the valve mechanism, these sections being taken respectively on the lines 40 5—5, 6—6, 7—7, 8—8, 9—9, 10—10 and 11—11 of Fig. 3.

Fig. 12 is another detail of construction, this figure showing the rear end of the valve casing in elevation.

Fig. 13 is a diagram showing the valve, cylinder and piston and the coacting ports and passages.

Like characters of reference designate corresponding parts in all the figures.

20 20 is the main casing and is constructed with two longitudinal bores 21 and 22. The bore 21 forms the main cylinder of the engine and 22 a valve casing chamber. A rear cylinder head 23 fits over this casing and 55 into the cylinder 21. It comprises a lug 24

of smaller diameter than that of the cylinder 21, which extends into this cylinder. It is constructed to form primary lugs 25 which project laterally in line with the cylinder bore 21, and with secondary lugs 26 which 60 project laterally in line with the valve chamber bore 22. It is provided with a port with which an air or water pipe may be connected and which leads to a central chamber 27, and with a threaded fluid pressure intake port 28 65 directly over the valve casing chamber.

The forward cylinder head is designated by 30. This fits into the main cylinder and over the valve casing chamber. Opposite the latter chamber it forms laterally projecting lugs 31 in line with the lugs 26, and between them is a threaded exhaust port 32. In line with cylinder 21 this forward head is provided with a longitudinal opening through which the piston extension 75 71 slides.

On the forward end of this cylinder head is a round boss 34 with its axis coincident with the axis of the main cylinder, over which boss fits the forward sleeve 35 within 80 which certain parts of the apparatus are supported. The rear portion of this sleeve is constructed to form projecting lugs 36 in alignment with the lugs 25.

40 40 is a handle bar from which extend supports 41 to a frame 42 which rests upon the rear cylinder head 23 and has holes therein which coincide with similar holes in the lugs 25. The main parts of the apparatus are held together by through-bolts 43 which pass 90 through the handle bar frame, lugs 25 and 36, and have nuts 44 on their outer ends. Between the nuts 44 and the forward side of lugs 36 compression springs 45 are interposed.

A similar arrangement is used to hold the rear and forward cylinder heads against adjacent ends of the valve chamber. In this case the through-bolts which are designated by 46, pass through the lugs 26 and 31; their 100 nuts are designated by 47 and the compression springs by 48.

Inside of the front sleeve 35 which is thus connected with the main part of the apparatus, is a rotary sleeve 50. The rear end 105 of this is of larger internal diameter than the rest of it and is provided with a ring of ratchet teeth 51. A pawl ring 52 is placed within this part of enlarged internal diameter and supports pawls 53 which are spring- 110

pressed into engagement with the ratchet teeth 51. The pawl ring is provided with a central opening through which the piston extension 71 slides, which is substantially cylindrical in cross-section except for two diametrically opposed ribs 54 which project into this opening and into inclined grooves 55 in the piston extension, by means of which it is oscillated by the reciprocations of the piston extension.

10 The forward end of the rotary sleeve 50 is cut back to form alternate projections 56 and depressions 57. 60 is a drill bit socket having a polygonal bore 61 adapted to receive a similarly shaped socket of a drilling tool (not shown). This is rotatively supported within the forward sleeve 35 and has an enlarged head 62 which rests upon a shoulder within the forward sleeve to prevent the drill bit socket from falling out. The rear end of the head 62 is constructed with depressions 63 into which the projections 56 on the forward end of rotary sleeve 50 extend, and with projections 59 which extend into the depressions 57.

25 64 is an anvil block within the rotary sleeve 50 and slidable therein. Its rearward movement is limited by an integral enlarged head 65 which abuts against an annular shoulder 58 formed inside of sleeve 50. The anvil block is also provided with a central axial hole 66.

30 70 is the piston and 71 an integral extension thereof. The rear end of the piston is provided with a recess 72 to permit the piston in its travel to pass over the lug 24. In the piston extension are two diametrically opposed longitudinal grooves into which fit ribs projecting from the forward cylinder head 30 to hold the piston against rotation. These parts are not shown as they form no part of this invention and are well known. There is a hole 73 through the center of the piston and piston extension.

35 45 74 is a tube, the rear end of which is flanged and held in place by a threaded plug 75 screwed into the rear cylinder head 23. The end of this plug is slotted at 76 to permit the passage of air or water from the chamber 27 to the tube 74. This tube passes through the piston and piston extension and its forward end is reduced in diameter as shown at 77 to pass through the hole 66 in the anvil block and into a hole through the 50 center of the drill bit, it being understood that when this tube 74 is used, hollow drill bits are to be used with the apparatus.

55 The valve casing is a cylindrical body arranged to fit into the valve chamber 22. 60 In the particular form shown the valve casing is made of a rear part and a forward part designated respectively by 80 and 81, both slotted on one side and held in alignment by the wall of the valve chamber and 65 in proper axial relation by means of a key

82 fitted into these slots and another slot in the wall of the valve chamber.

Through the center of the valve casing is a bore 83 and at each end thereof alining bores 84-85 of smaller diameter. 86 is a fluid pressure supply chamber formed in the rear end of valve casing member 80, and 87 is an exhaust chamber formed in the forward valve casing member 81. 88 and 89 are hollow screw plugs in the main casing 75 20 at the ends of the valve casing and adjacent the intake opening 28 and the exhaust opening 32 respectively.

Within the valve casing is a reciprocatory valve which comprises three intermediate 80 rings or pistons 90-91 and 92 of a diameter to make a sliding fit in the bore 83, and two end rings or pistons 93-94 of a diameter to make a sliding fit in the bores 84 and 85. These rings or pistons are equally spaced 85 and are integral with a central spindle 95 which extends a short distance beyond the end rings as at 96 and 97.

The outer wall of the valve casing is cut away for the greater part of its length as 90 at 100 to form a passage which is connected by ports 101 with supply chamber 86.

A port 102 connects passage 100 with the interior of the valve casing part 80, and another port 103 connects the same passage 95 with the interior of valve casing part 81.

On another side the valve casing is cut away in a similar manner as at 104 to form a passage for the exhaust and this is connected by ports 105 with the exhaust chamber 87. A port 106 connects passage 104 with the central part of the interior of the valve casing. 107 is a port between exhaust passage 104 and the interior of the smaller bore 84 about midway of its length. From 105 the other smaller bore 85 is a similar port 108 leading to exhaust passage 104.

100 The valve pistons and ports are so proportioned and arranged that when the valve is in its central position, its pistons 90, 91, 110 92, 93 and 94 will register with and close ports 102, 106, 103, 107, 108 respectively. The valve pistons and ports are of the same width so that a movement of the valve from its central position in either direction, will 115 open all of these ports.

110 107^A is a narrow extension of port 107 on the rear side thereof, and 108^A is a similar extension of port 108 on the forward side thereof. Thus when the valve is in its central position to close all of the ports, both 120 of these port extensions are open.

125 Between the passages 100 and 104 the rear part 80 of the valve casing is cut away as at 110 to form a passage from the interior of the valve casing to the rear part of the main cylinder 21. A port 111 connects this passage with the interior of the valve casing. The forward part 81 of the valve casing is cut away as at 112 to form a passage 130

from the interior of the valve casing to the forward part of the main cylinder. This passage is connected with the interior of the valve casing by means of a port 113. 114 designates main ports through main casing 20 between the rear end of the main cylinder 21 into the valve chamber 22 communicating with passage 110. 115 are ports through main casing between the forward 10 end of the main cylinder to the valve chamber communicating with the passage 112.

A groove 120 is cut in the wall of the valve casing part 80 between passages 104 and 110 and a hole 121 is drilled from the 15 groove into the rear end of the interior of the valve casing. 122 is a port through the main casing between the main cylinder and the groove 120.

123 is a similar groove in valve casing 20 member 81; 124 a hole leading therefrom to the forward end of bore 85, and 125 a port through the main casing between the main cylinder and the groove 123.

The operation of the device is as follows:—Assuming that fluid pressure such for example, as compressed air, is supplied to the device through the port 29, the reciprocating valve is in the position in which it is shown in the drawings, and that the main 25 piston 70 is at the rear end of its stroke, the fluid pressure is in communication through ports 101, passage 100, port 102 to the interior of the valve casing between the valve pistons 90 and 91 out through port 111, passage 110, and ports 114 into the rear end 30 of the main cylinder. At the same time the part of the main cylinder which is forward of the piston will be in communication through the ports 115 with the passage 112 35 through port 113 with the interior of the valve casing between the pistons 91 and 92 and through the port 106 with the exhaust passage 104 which communicates through 40 ports 105 with the exhaust port 32 to the atmosphere. This will cause the piston 70 to be pushed forward.

As soon as the main piston reaches such a position that its rear edge will uncover port 122, the pressure of the fluid within 50 the main cylinder will pass through this port into the groove 120 and through the hole 121 into the rear end of the valve casing, back of the rear piston 93. This will result in the fluid pressure acting upon the 55 rear surface of the piston 93 and the valve will be pushed forward thereby against the pressure which through port 103 is present between the spools 92 and 94, the difference in area between these two spools having been 60 depended upon to hold the valve in its rear position up to this point of the operation.

When the reciprocating valve reaches its central position, its piston 92 closes port 103 to cut off pressure supply between pistons 65 92 and 94; its piston 93 will close port 107;

its piston 90 will close port 102, and its piston 91 will close port 106. At the same time piston 93 will uncover the port extension 107^a. This is smaller in area than is port 121 so that while the pressure back of piston 70 93 which is depended upon to move the valve, will be reduced, enough of this pressure will remain to insure the further forward movement of the valve.

Further movement of the valve will cause 75 piston 90 to open port 102 to introduce pressure back of piston 90 to cause the valve to continue its stroke. As soon as piston 90 begins to open port 102, piston 93 will begin to open port 107 to release the pressure back 80 of piston 93. When the valve has completed its forward movement piston 91 will have fully crossed port 106 so that there is free escape of pressure from the rear end of the main cylinder to the atmosphere, and 85 piston 90 will have fully crossed port 102 to admit pressure to the forward side of the main piston. Under these conditions the main piston will be moved back.

During the forward movement of the 90 valve, the port extension 108^a will delay the closing of the outlet from the space within bore 85 so that a smaller amount of air will be entrapped within this space than would be if the port extension were not present. 95 This results in diminishing the cushioning effect of the air entrapped in this space.

The main piston will then continue its forward movement until it reaches the end of its stroke. The reciprocating valve has, 100 as just described, been forced forward so that the fluid pressure supply is now admitted through passages 100 through port 103 between valve pistons 91 and 92 through port 113, passage 112, and ports 115 to the part 105 of the main cylinder forward of the main piston. At the same time the passage has been opened through the rear end of the main cylinder through ports 114, passage 110, port 111, between valve spools 90 and 91, through port 111, through port 106 to exhaust passage 104. This will cause the main piston to be forced rearwardly.

As soon as it reaches such a position that the forward edge of the main piston 70 uncovers port 125, fluid pressure therein will be admitted to the forward end of the interior of the valve casing through the hole 124 to force the reciprocating valve rearwardly in a similar manner to that already 120 described for the forward stroke.

The shank of the drill bit is of sufficient length to extend beyond the socket 60 into such a position that the anvil block 57 will rest upon it so that the blows of the piston 125 extension upon the anvil block will be transmitted to the drill bit.

When it is desired to use a cleansing fluid, such as air or water, or both, this fluid is led into the chamber 27 and has free com- 130

munication through the slot 76 with the interior of tube 74, the forward narrowed portion 77 of which extends into a hole of the drill bit so that the desired cleaning fluid 5 will be forced directly through the drill bit into the bottom of the hole being drilled.

This drill has the advantage of having all of its fluid passages short and direct, its valve action is very quick acting and gives 10 the apparatus a high efficiency. The whole construction is rugged and simple. It is not my intention to limit myself to the exact construction shown which is merely illustrative of a preferred form of construction, 15 but intend only such limitations as are imposed by the following claims.

What I claim is:

1. A rock drill comprising a cylinder, a piston therein, a valve casing having a central chamber with cylinder ports connected with the ends of the cylinder beyond the ends of the piston travel and having pressure and exhaust ports, said valve casing also having end chambers of less area than 25 that of the central chamber, passages from the cylinder within the ends of the piston travel to the ends of the corresponding end chambers, a reciprocatory valve in all of said chambers arranged to be moved beyond its 30 central position by motive fluid from the cylinder through said passages, and arranged to alternately connect the cylinder ports with the supply and exhaust ports, a relief port in said end chambers intermediate 35 the ends thereof, each of said relief ports having a port extension of less area than that of said passages arranged to be opened by the valve in its central position to allow a part of the valve actuating fluid to escape 40 from the end chambers.
2. A rock drill comprising a main cylinder and a piston therein, a valve casing having a central bore with cylinder ports connected with the ends of the main cylinder 45 beyond the ends of the piston travel, and having pressure and exhaust ports, said

valve casing also having alining end bores of smaller diameter, passages from the main cylinder within the ends of the piston travel to the ends of the corresponding end bores, 50 and a piston valve comprising end pistons fitting the end bores and intermediate pistons fitting said central bore spaced from said end pistons and from each other, relief ports in the end bores intermediate their 55 ends, each of said relief ports having a port extension of less area than that of said passages, on the sides of the relief ports toward the ends of the end bores.

3. A rock drill comprising a main cylinder and a piston therein, a valve casing having a central bore with cylinder ports connected with the ends of the main cylinder beyond the ends of the piston travel, and having pressure and exhaust ports, said 60 valve casing also having alining end bores of smaller diameter, passages from the main cylinder within the ends of the piston travel to the ends of the corresponding end bores, and a piston valve comprising end pistons 65 fitting the end bores and intermediate pistons fitting said central bore spaced from said end pistons and from each other, relief ports in the end bores intermediate their ends, said pistons being arranged to close 70 all of said ports when the valve is in its central position and to open all of said ports when the valve is moved in either direction from its central position, each of said relief ports having a port extension of less area 75 than that of said passages, on the sides of the relief ports toward the ends of the end bores, said valve pistons being so arranged that when moved beyond their central position to lead pressure between two of the 80 larger pistons to the cylinder, pressure is present between another of the larger pistons and the adjacent end piston to complete the movement of the valve.

In witness whereof, I have hereunto set 85 my hand this 20 day of April, 1917.

THOMAS E. STURTEVANT.
